UNITED STATES PATENT OFFICE.

CHARLES G. SCHNELL, OF NORTH TONAWANDA, NEW YORK, ASSIGNOR TO RUDOLPH WURLITZER MANUFACTURING COMPANY, OF NORTH TONAWANDA, NEW YORK, A CORPORATION OF NEW YORK.

PNEUMATIC ACTION FOR MUSICAL INSTRUMENTS.

Application filed May 24, 1922. Serial No. 563,183.

To all whom it may concern:

Be it known that I, CHARLES G. SCHNELL, a citizen of the United States, residing at North Tonawanda, in the county of Niagara and State of New York, have invented new and useful Improvements in Pneumatic Actions for Musical Instruments, of which the following is a specification.

This invention relates to the pneumatic actions of player pianos and other automatic musical instruments and more particularly to actions having unit valve-blocks.

Its object is to improve the construction of such valve-blocks with a view of facilitating their application to and removal from the customary channel board and avoiding the necessity of removing and replacing the usual air tube nipples in making repairs.

In the accompanying drawings: Figure 1 is a transverse section of a pneumatic action equipped with the improved valve blocks. Figure 2 is a fragmentary front view, partly in section, of the channel board and valve blocks. Figure 3 is a vertical section 25 of one of the valve blocks, on an enlarged scale. Figure 4 is a horizontal section on line 4—4, Fig. 3.

Similar characters of reference indicate corresponding parts throughout the several views.

The pneumatic action, to which my improved valve block is applicable, may be of any suitable or well known construction, but as shown in the drawings, the same comprises an upright channel board 10, rows of striker pneumatics 11 mounted on the rear side of said board, and corresponding rows of valve blocks or units 12 mounted on the front side of said board. These pneumatics are carried by horizontal channel boards or shelves 13 to the undersides of which their fixed boards are glued or otherwise fastened. The upright channel board 10 is provided with longitudinal vacuum channels 14, one for each row of valve blocks and the companion striker pneumatics. The several vacuum channels communicate at their ends with a manifold passage 15 which is connected by a trunk 16 with the usual main exhaust bellows, not shown, so that said channels are constantly exhausted during the operation of the instrument.

The valve blocks 12 are detachably secured to the channel board 10 by screws 17 or the

like, which preferably pass through openings 18 in diagonally opposite corners of said blocks, as shown in Figs. 2 and 3. In the example illustrated in the drawings, each block contains a lower pouch chamber 19 connected by a passage 20 with the corresponding vacuum channel 14 of said board, and an upper valve chamber 21 connected with the corresponding striker pneumatic 11 by a channel 22 extending transversely through said channel board and the corresponding shelf 13, the passage 20 and channel 22 of each block being arranged one above the other and both extending through the rear side of the block. The upper valve chamber 21 communicates with the atmosphere through a flushing port 23 and the partition 24 of the block contains a vacuum port 25. Located in said upper valve chamber is a duplex-valve 26, the heads of which co-operate with the vacuum and vent ports 25 and 23, respectively, to open the one when the other is closed and thereby collapse or inflate the corresponding striker pneumatic in the usual manner.

Arranged in the bottom of the lower chamber 19 of the block is the customary valve operating pouch 27 which may be glued or otherwise secured to a retaining ring 28 seated in the bottom of said block. The outer face of this ring is flush with the face of the block and a sealing sheet 29, preferably of frangible material, as paper, is glued to said face to form an air-tight chamber 30 underneath the pouch. Leading from the corresponding tracker duct 31 to this chamber is the usual flexible tube 32 which is connected at its lower end to an elbow-shaped metallic nipple 33 inserted in the outer end of a transverse passage 34 formed in the block. Said passage communicates with the chamber beneath the pouch 27 through a branch passage 35 extending downwardly and inwardly from the transverse passage. The nipple 33 is usually held in place by glue or shellac to reliably seal the passage 34.

The main rear portion of the passage 34 is arranged under and substantially in vertical alignment with the left hand screw-opening 17 of the block, as shown in Fig. 3, and said passage is substantially parallel with the adjacent side of the block, as shown in Fig. 4, while its front portion is diagonal and deflected inwardly or toward the opposite side

of the block and terminates at the face thereof. The shank or horizontal portion of the nipple 33 is arranged in the diagonal portion of the passage 34 with its inner side at an acute angle to the face of the block, as shown in Fig. 4, bringing its projecting upright portion on the inner side of the upper left hand fastening screw 17 of the block. This arrangement permits the nipple to remain fixed and undisturbed when it is desired to remove the block for making repairs. Heretofore this nipple was in some cases located directly under the adjacent attaching screw of the block and its angular outer portion stood directly in front of the screw, necessitating breakage of the sealed nipple-joint in order to turn the nipple aside and afford access to said screw for removing the block and requiring the nipple to be resealed after replacing the block. The time incident to such re-sealing is saved by the present novel arrangement and the liability of neglecting that act in replacing the block is also avoided.

25 I claim as my invention:

1. A unit valve-block for pneumatic musical instruments, comprising a valve chamber having exhaust and flushing ports, valves controlling said ports, a pouch chamber containing a pouch for actuating said valves, an atmospheric chamber underneath the pouch and a passage located near one side of the

block and leading to said atmospheric chamber, said block having a screw-opening extending rearwardly from its face, and located 35 near the same side thereof as said passage, and an elbow-shaped nipple connected to said passage and having its shank portion extending diagonally from the block with its inner side at an acute angle to the face 40 of the block, whereby the projecting portion of the nipple is offset relative to said screw-opening.

2. A unit valve-block for pneumatic musical instruments, comprising a valve-chamber 45 having exhaust and flushing ports, valves controlling said ports, a pouch chamber containing a pouch for actuating said valves, an atmospheric chamber underneath the pouch and a passage located near one side of the block and leading to said atmospheric chamber, the main rear portion of said passage being substantially parallel with the adjacent side of the block, while its front portion is diagonal and deflected inwardly 50 toward the opposite side of the block, the latter having a screw-opening arranged above and substantially in vertical alinement with the main portion of said passage, and an elbow-nipple having its shank arranged 55 in the diagonal front portion of said passage, whereby its projecting upright portion is offset relative to said screw-opening.

CHARLES G. SCHNELL.
